UNITED STATES PATENT OFFICE.

HERMANN BAUMANN, OF ADAMS, MASSACHUSETTS, ASSIGNOR OF ONE-HALF
TO ROBERT N. RICHMOND, OF SAME PLACE.

FLOAT-DETECTING ATTACHMENT FOR LOOM-SHUTTLES.

SPECIFICATION forming part of Letters Patent No. 449,194, dated March 31, 1891.

Application filed April 23, 1890. Serial No. 349,075. (No model.)

To all whom it may concern:

Be it known that I, HERMANN BAUMANN, a citizen of the United States, and a resident of Adams, in the county of Berkshire and State 5 of Massachusetts, have invented new and useful Improvements in Float-Detecting Attachments for Loom-Shuttles, of which the following, taken in connection with the accompanying drawings, is a specification.

10 This invention relates to improvements in loom-shuttle attachments for preventing misweaving caused by the breaking of one or more of the warp-threads or by threads or other articles being thrown on or accidentally intermixed with the warps of a loom at any place between the woven cloth and the harness during the process of weaving cloth of any kind. Such break of the warp thread or threads or accidental intermixture with 15 articles of any kind causes entanglement and tightening of the said warp and prevents a free passage of the loom-shuttle.

To prevent misweaving, as above stated, I provide a loom-shuttle with a device which 20 is automatically actuated by the tightening of the warp-threads, causing a spring-pressed lever arranged on the under side of the shuttle to be pressed upward, causing a spring-pressed gate, lever, or filling-thread breaker 25 to be released and forced by the influence of its spring against the cop-spindle, by which the filling-thread is broken at the same time as the said gate or lever is forced against the cop, spindle, or bobbin.

30 In connection with such improved loom-shuttle attachment I use any of the well-known automatic stop-motion devices for automatically stopping the loom by the breaking of the filling-thread to enable the operator to remedy the entanglement or breaking of the warp-threads before any misweaving occurs. Such automatic stop-motion, not forming any part of my present invention, is not represented in the drawings.

40 My improved loom-shuttle attachment is constructed as follows, reference being had to the accompanying drawings, wherein—

Figure 1 represents a top view of a loom-shuttle provided with my improved attachment, showing parts in section. Fig. 2 represents a side elevation of the same, showing

a part of the shuttle as being broken away. Fig. 3 represents a cross-section on the line X-X shown in Fig. 2. Fig. 4 represents a detail perspective view of my improved loom-shuttle attachment, showing the gate or filling-thread breaker as released. Fig. 5 represents a detail side elevation of the frame or case for the attachment. Fig. 6 represents a detail side elevation of the lever by which the filling-thread breaker is held in its normal position. Fig. 7 represents a detail side view of the gate or filling-thread breaker; and Fig. 8 represents on a reduced scale the position of the shuttle relative to the warp-threads, 55 woven cloth, reed, and harnesses in a loom.

Similar letters refer to similar parts wherever they occur on the different parts of the drawings.

a represents the loom-shuttle body as usual, 70 on which b is the pivoted cop-spindle, c the cop, and c' the filling-thread, which in operation will pass from the cop through the shuttle-eye a' in the ordinary manner.

The improved attachment consists of a frame 75 D, preferably made of sheet metal and secured in a suitable manner on the interior of the shuttle, as shown. The frame D is preferably provided with inclosing ribs or edges d d d, which are preferably made in one piece with 80 the main portion D. D' is a spring for actuating the filling-thread breaker, which spring is preferably made in one piece with the case or frame D, as shown in Fig. 5. D'' D'' are ears on the plate or frame D, to which is pivoted the gate or filling-thread breaker E, preferably provided with a forked, serrated, or corrugated end E', which is automatically forced against the cop-spindle or bobbin as soon as it is released. e is a locking projection on the gate or filling-thread breaker E. 85

The frame D has a side projection on arm D'', preferably made in one piece with it, to which is pivoted at f the gate-releasing lever or arm F, which is held in its normal lower 90 locked position relative to the gate E by the influence of a suitable spring F', as shown.

The lever F is provided with a hooked projection F'', adapted to engage with the gate projection e for the purpose of holding the 100 gate E in its normal position during the regular process of weaving the cloth. F''' is a stop

projection on said lever F, which is adapted normally to rest on a lip or projection D⁴ on the frame D for the purpose of preventing said lever from dropping down below the under side of the loom-shuttle. The lever F has on its under side near its free end a cam-shaped projection F⁴, extending to near the under side of the loom-shuttle, but not below the latter, and where such projection is located 10 I make a cut-away portion a'' on the under side or edge of the shuttle for the purpose of guiding the entangled or tightened warp-thread to and against such projection F⁴ on the lever F, as shown in Fig. 2.

15 In Fig. 8, G represents the woven cloth; G' and G'', the warp-threads during the ordinary course of weaving; g' and g'', the entangled upper and lower warp-threads; h, the reed, and i i the harnesses.

20 The operation of the device is as follows: During the ordinary and regular weaving process the gate or filling-thread breaker E is held by the spring-pressed lever F in its normal position within the frame D d. If from 25 any cause the warp-threads become twisted or entangled, as shown at g' g'' in Fig. 8, the lower thread g'' will be pressed against the lower edge of the shuttle-body a, and as the latter advances the tightened or entangled warp 30 will be guided into the cut-away portion a'' on the under side of the shuttle-body and against the under side of the yielding lever F, causing the latter to be swung upward sufficiently to disengage itself from the gate or 35 filling-thread breaker E, which being liberated is instantly swung outward against the cop-spindle or bobbin b, Fig. 1, by the influence of the spring D', by which action the free delivery of the filling-thread from the cop or 40 bobbin is prevented, causing such thread to break. The breaking of the filling-thread causes the loom to be stopped by any of the usual automatic devices used for this purpose, as hereinabove mentioned, thus preventing 45 misweaving. After the loom has been stopped and the entangled warp-threads adjusted the

gate or bar E is swung back to its normal position and locked by the hooked projection F'' of the lever F, the filling-thread is tied, and the loom set in operation, and so on. 50

Heretofore in devices of this kind the gate-releasing lever or projection has been arranged at the upper edge of the shuttle; but this is objectionable, for the reason that such upwardly-projecting releasing-lever is liable to be tripped by slack threads in the warp, causing unnecessary breakage of the filling-thread. Such objection is entirely overcome by locating said releasing lever or projection at the under side of the shuttle, as shown in 60 Fig. 1.

In practice I have found that if the warp-thread is broken or entangled the filling-thread-breaking device is more quickly actuated for breaking the filling-thread and stopping the loom when the release-lever is arranged on the under side of the shuttle, as compared with devices having such release-lever arranged at the upper edge of the shuttle. 65

Having thus fully described the nature, construction, and operation of my invention, I 70 wish to secure by Letters Patent and claim—

The combination of the shuttle-body and its bobbin or cop-spindle, the case or frame D, secured to the shuttle-body and having a 75 spring D', the filling-thread breaker E, pivoted to said frame and having a lock projection e, and a spring-pressed gate holding and releasing lever F, having a hook F'' for retaining the gate E in its normal position and 80 having a stop projection F³ adapted to rest normally against a projection D⁴ on the frame D, substantially as and for the purpose set forth.

In testimony whereof I have signed my 85 name to this specification, in the presence of two subscribing witnesses, on this 18th day of April, A. D. 1890.

HERMANN BAUMANN.
